UNITED STATES PATENT OFFICE.

ULYSSES G. LEE, OF CHICAGO, ILLINOIS, ASSIGNOR TO MONTAGUE MAILING MACHINERY CO., A CORPORATION OF TENNESSEE.

ADDRESSING-MACHINE.

1,122,617.

Specification of Letters Patent. Patented Dec. 29, 1914.

Application filed April 29, 1914. Serial No. 835,262.

To all whom it may concern:

Be it known that I, ULYSSES G. LEE, a citizen of the United States, residing at Chicago, Illinois, have invented certain new and useful Improvements in Addressing-Machines, of which the following is a specification.

My present invention relates to a machine for printing public service bills or the like, being similar to that disclosed in application for Letters Patent of the United States filed by me April 15, 1912, #690,905, my present invention including means for preventing the record plates being taken from the hopper except at predetermined intervals, so that the record plates will be spaced apart at intervals on the feeder to permit making a series of impressions from each plate as it is passing under the impression head. One result that may be accomplished by this machine is the printing, for instance, of bills having attached thereto one or more coupons so that the impression may be made on the coupons as well as on the main portion of the bill.

In the accompanying drawings, I have shown an example of my invention in which—

Figure 1 is a front view, and Fig. 2 is a detail cross sectional view with some of the parts in elevation and some parts in dotted lines. Fig. 3 is a detail view of means for giving a step by step movement to the plate feeder.

The address or record plates employed are those used in the Montague system, though the invention is not limited in this respect. The impression head may be of various forms, but in the particular construction shown it consists of a bar 1 which is reciprocated vertically through rods 2 from any suitable driving mechanism. The bar 1 carries the impression means, and while this means may assume various forms I show in the example illustrated a series of impression pads 3 adjustably mounted at 4 on the impression bar 1, so that they can be set at different points along this bar or removed.

Various forms of feed means may be employed for moving the record plates to the printing point or to the several printing points, and as an example of any such means I show an endless chain 5 the upper

stretch of which passes along a table 6 and is provided with dogs 6' spaced apart a little more than the length of the record plates which are indicated at a. These record plates are guided along a channel or way indicated at 7, 7', and they are taken from a hopper indicated diagrammatically at 8, in which hopper the plates are arranged in a pile, the feed dogs taking hold of the lowermost one of the pile. The feeder passes around a driving sprocket 9 which may be driven in any suitable way step by step, and about another sprocket 10. More or less of the impression pads 3 may be used, and when one pad is used the machine may be employed to secure an impression successively or from one plate after another by simply supplying the record plates one to each dog of the chain, or other form of feeder, each action of the plate feeder bringing a plate under the impression pad. Such use would be, for instance, where it is desired to address envelops. Where it is desired to make a plurality of impressions, for instance on a coupon bill, or upon a sheet or form, together with a separate record strip, a plurality of impression pads are employed to make up the impression member, and we will suppose as an instance that three such pads are employed as shown in Fig. 1. From each plate, therefore, three impressions would be taken as the plate moves under the impression head made up of the three pads, and the next following plate would not come into action beneath the impression head until the impressions had been made from the first plate, and this had been moved from under the impression head toward the left to be discharged from the machine or into a suitable stacker hopper or chute.

For determining the spacing of the plates various means might be employed, but in the particular construction shown a lifting finger or bar 11 is used extending up through an opening in the table 6. The lower end of this lifting finger is connected with a lever 12 controlled by a roller 13 thereon and a cam 14 on the shaft of the chain wheel 10. The cam is of such form that in the step by step movement of the plate feeder the lifting finger 11 will be in an elevated position during two movements of the feeder, and thus during these two actions no record plate will be taken from the

hopper 8, and therefore two of the feed dogs will be empty. At the next feeding action, however, the lifting finger 11 will be lowered and the feed dog will take the 5 lowermost plate and feed it toward the impression point, and on arriving under the first impression pad, *i. e.*, at the right of the set shown, an impression will be made, and at the next plate feeding action this 10 plate will be shifted under the second impression pad, and an impression will be made here on the form or sheet, but as the preceding dog and the following dog are empty, no impressions will be made at either 15 the first or the third impression pads. The next action will carry the record plate to the third pad, and empty dogs will be adjacent the first and second pads. An impression will then be made at the third pad when the 20 cross head comes down, but no impressions will be made at the first and second pads. The next action of the feeder will carry the record plate which has now completed its work from under the third pad, and the next 25 following record plate will be located under the first pad, that is, the pad at the right of the set shown. It will be seen from the above that the machine is organized to feed record plates in close order so that for in- 30 stance in feeding envelopes an impression can be made from a separate plate at each stroke of the impression head, or the plates may be fed at intervals, as just described, and a series of impressions taken from the 35 said plate upon its assuming different positions under the impression means, which may be formed of the separate pads shown, or of other forms. When the plates are to be fed in close order, one for each dog, the 40 lifter 11 is made inoperative, and this may be done in any suitable way by detaching the lifter from the machine. It will be understood also that the machine may be organized to secure any desired spacing of the 45 record plates by changing the mechanism for operating the lifter, that is to say, every other feed dog may be empty or two dogs may be empty, as in the example shown. Any suitable form of inking ribbon mech- 50 anism may be employed well known in the art.

As in the application above mentioned, automatic feed mechanism may be employed for feeding the forms or sheets to receive 55 the impressions, and this mechanism may be similar to that described in said application or of other forms. By any suitable arrangement of change speed mechanism the feeding means for the forms may be set to 60 allow the sheet or form which is to receive the impression to remain at rest for either one impression stroke or for a plurality of strokes of the impression head, or the machine may be fed by hand.

65 While the feeder for the record plates

may be of different forms and different means employed for giving it a step by step movement, I would mention as an instance of means that may be used that shown in Letters Patent of the United States granted 70 to me January 16, 1912, #1,014,762.

In Fig. 3 is shown a pawl 15 carried by a wheel or disk 16 loose on the shaft 9' of the driving sprocket 9, said pawl engaging the toothed block 17 fixed on said shaft. The 75 disk 16 is oscillated and its pawl therefore gives a step by step forward movement to the shaft 9' on which it is supported and to the sprocket fixed on said shaft. It is moved in one direction by a chain 18 connected 80 with any suitable moving part of the machine, and in the other direction it is moved by a chain 19 and a spring 20, the latter being attached to any suitable frame part.

I claim as my invention:—

1. In combination impression means disposed at a plurality of impression points, record plates, feed means for moving said record plates *seriatim* to and past the impression points, and means for automatically 90 supplying the record plates to and spacing them in relation to the feeder means distances apart to permit each plate to make impressions at different impression points and pass out of range of said impression 95 means before an impression is made from the next following record plate on the feed means, substantially as described.

2. In combination impression means disposed at a plurality of impression points, record plates, feed means for moving said record plates *seriatim* to and past the impression points, and means for automatically 100 supplying the record plates to and spacing them in relation to the feeder means distances apart to permit each plate to make impressions at different impression points and pass out of range of said impression means before an impression is made from the next following record plate on the feed 105 means, said plate supplying and spacing means comprising a hopper, and means at said hopper to eliminate at times the function of the plate feeder means of taking plates from said hopper, substantially as 110 described.

3. In combination impression means disposed at a plurality of impression points, record plates, feed means for moving said record plates *seriatim* to and past the impression points, and means for automatically 120 supplying the record plates to and spacing them in relation to the feeder means distances apart to permit each plate to make impressions at different impression points 125 and pass out of range of said impression means before an impression is made from the next following record plate on the feed means, said plate supplying and spacing means comprising a hopper, and a lifter at 130

said hopper to lift the pile of plates to prevent the feeder means from engaging the lowermost plate, substantially as described.

4. In combination impression means disposed at a plurality of impression points, record plates, plate feeder means having dogs for moving said plates to and past the impression points *seriatim*, and means for automatically supplying said plates to the 10 feeder means at intervals to space the plates thereon and leave some of the dogs empty, substantially as described.

5. In combination impression means disposed at a plurality of impression points, 15 record plates, a hopper therefor, plate feeder means, and means for eliminating at times the function of the plate feeder means comprising a lifting finger to engage the plates, and a cam for operating the lifting finger, 20 substantially as described.

6. In combination impression means having a plurality of removable and adjustable impression heads, record plates, feeder means for the plates having dogs thereon for engaging the plates and spaced apart to bring 25 plates in succession to an impression point, means for supplying the plates to the feeder means and automatically spacing the plates

thereon to leave some of the dogs empty, substantially as described.

7. In combination impression means, a hopper for record plates, feeder means having devices spaced apart along the same for feeding the plates from the hopper to the impression means, and means for automatically leaving certain of said devices empty to thereby eliminate the function of said certain devices of feeding plates to the impression point; substantially as described.

8. In combination impression means, a 40 series of record plates, feed means for the record plates having devices for engaging the record plates, and means for automatically supplying the record plates to and spacing them in relation to the feeder means 45 to leave certain of said devices empty to thereby eliminate at certain times the function of said feeder means of presenting a plate to said impression means, substantially as described.

In testimony whereof, I affix my signature in presence of two witnesses.

ULYSSES G. LEE.
